US00D976585S

(12) **United States Design Patent** (10) **Patent No.:** **US D976,585 S**
(45) **Date of Patent:** **** Jan. 31, 2023**

(54) **CASE**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Abidur Rahman Chowdhury**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Sung-Ho Tan**, San Francisco, CA (US); **Clement Tissandier**, San Francisco, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/741,988**

(22) Filed: **Jul. 17, 2020**

Related U.S. Application Data

(63) Continuation of application No. 29/705,726, filed on Sep. 13, 2019, now Pat. No. Des. 953,739.

CLAIM

The ornamental design for a case, as shown and described.

DESCRIPTION

FIG. 1 is a front view of a case showing the claimed design;
FIG. 2 is a rear view thereof;

FIG. 3 is a side perspective view thereof;

FIG. 4 is a bottom rear perspective view thereof;

FIG. 5 is a top front perspective view thereof; and,

FIG. 6 is a top rear perspective view thereof.

The background in the Figures forms no part of the claimed design.

The dot-dash broken lines in the Figures and the faded areas within the dot-dash broken lines show portions of the case that form no part of the claimed design.

1 Claim, 3 Drawing Sheets
